(57) **CLAIM**

The ornamental design for a hoist scale, as shown and described.

DESCRIPTION

FIG. 1 is a perspective view of a hoist scale showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and

FIG. 7 is a bottom plan view to that shown.

FIG. 8 is a perspective view of showing the top and bottom of a hoist scale are connected with a rectangle block with an arc block and another rectangle block respectively of claimed design; and,

FIG. 9 is a perspective view of showing the top and bottom of a hoist scale are connected with a rectangle block with an arc block and a column respectively of claimed design.

The broken line showing is for illustrative purposes only and forms no part of the claimed design.
